CLAIM

The ornamental design for a tropic traveler shirt, as shown
and described.

DESCRIPTION

FIG. 1 is a front elevational view of a tropic traveler shirt
showing my new design;

FIG. 2 is a rear elevational view thereof;

FIG. 3 is a top right front perspective view thereof;

FIG. 4 is a top right perspective view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown on the pockets are understood to
represent conventional stitching.
